SWITCH FOR POLEHEADS

Filed Aug. 8, 1927

FIG. 1.

FIG. 2.

FIG. 3.

Inventor:
Frederick F. Brand,
by *Alfred S. Lutz*,
His Attorney.

Patented Mar. 19, 1929.

1,706,140

UNITED STATES PATENT OFFICE.

FREDERICK F. BRAND, OF PITTSFIELD, MASSACHUSETTS, ASSIGNOR TO GENERAL ELECTRIC COMPANY, A CORPORATION OF NEW YORK.

SWITCH FOR POTHHEADS.

Application filed August 8, 1927. Serial No. 211,411.

My invention relates to switches for pothead and more particularly to an improved switching arrangement in a pothead of an oil immersed electrical apparatus such as 5 a transformer. A cable, which may be underground, is often connected to a terminal of such apparatus by a switch or connector in a pothead mounted on the apparatus casing and containing insulating oil or compound 10 which surrounds and insulates the connector. It is customary to make periodic tests of a cable of this nature by applying to the cable conductor or conductors a voltage high enough to detect any weakness in the cable 15 insulation. While these tests are being made, the cable should be disconnected from other circuits and apparatus so that the results of the tests may not be affected by conditions outside the cable. It has been inconvenient, 20 to make such tests, however, because the pothead cover had to be taken off and the oil or compound removed before the connector could be opened and the testing apparatus connected to the cable. The general object 25 of the invention is to provide an improved switching arrangement for potheads adapted to permit disconnection and testing of a cable without opening the pothead or removing any insulating oil or compound contained in 30 the pothead.

The invention will be better understood from the following description taken in connection with the accompanying drawing in which Fig. 1 is a sectional view of a pothead 35 mounted on an electrical apparatus casing and provided with a switching arrangement in accordance with the invention, Fig. 2 is a sectional view of the pothead with the switch in open position, and Fig. 3 is an enlarged sectional detail view.

Like reference characters indicate similar parts in the different figures of the drawing.

In the arrangement shown in the drawing, a pothead 10 is mounted on a casing 11 45 adapted to contain electrical apparatus such as a transformer. The casing 11 may contain a body of insulating oil 12 in which the electrical apparatus is immersed. A switch 13 is enclosed in the pothead 10 to connect a lead 14 from the electrical apparatus to the conductor 15 of a cable 16 which also enters the pothead. The pothead may contain a body of insulating material such as oil or compound in which the switch 13 and the 55 terminals of the lead 14 and cable conductor

15 are immersed. The connecting blade of the switch 13 has an arm 17 to the outer end of which is connected an operating rod 18. This operating rod 18 extends through a stuffing box 19 sealed onto the inner end of an 60 insulating bushing 20 mounted through an opening in the pothead 10. The length of the operating rod 18 is preferably such that it projects only a short distance through the stuffing box 19 so that its free or outer end 65 is inside of and well protected by the bushing 20. A cap 21 may be secured over the outer end of the bushing 20 for additional protection.

During normal operation of the apparatus 70 in the casing 11, the switch 13 is of course closed to connect the apparatus to the cable 16 as shown in Fig. 1. When it is desired to test the cable 16, it may be quickly and conveniently disconnected from the apparatus 75 in the casing 11 without the necessity of opening the pothead 10 by pulling the operating rod 18 to open the switch 13 as shown in Fig. 2. A handle 22 in the form of an insulated rod may be conveniently used to open 80 or close the switch 13, the adjacent ends of the handle 22 and the rod 18 being arranged in any suitable way for detachable engagement as by being threaded as shown most clearly in Figs. 2 and 3. The outer end of 85 the insulated rod 22 is provided with a terminal 23 and the rods 22 and 18 and the arm 17 of the switch are of conductive material so that a conductive path is formed from the terminal 23 to the conductor 15 of the cable 90 16, the cable conductor 15 being connected to the same switch terminal which supports the connecting blade of the switch and its arm 17. Thus, a high voltage may be conveniently applied to the terminal 23 by means of suitable 95 testing apparatus to indicate the electrical condition of the cable 16 and its insulation, the switch 13 having been first opened, of course, by pulling the handle 22 outwardly so that the indications obtained from the testing apparatus may not be influenced by anything outside the cable. After the tests have been completed, the cable may be again connected to the apparatus in the casing 11 merely by pushing in the handle 22 to close 100 105 the switch 13, the handle being then detached from the rod 18 and removed and the protective cover 21 replaced in position over the outer end of the bushing 20.

While the invention has been explained 110

by describing and illustrating a preferred embodiment thereof, it will be apparent that changes may be made without departing from the scope of the invention as defined in the 5 appended claims.

What I claim as new and desire to secure by Letters Patent of the United States is:

1. The combination with electrical apparatus of a pothead, a cable entering said pothead, a switch enclosed in said pothead for connecting said cable to said apparatus, and conductive switch operating means conductively connected to said cable while the switch is open and extending to a point accessible 10 while said pothead is closed, whereby said cable may be disconnected from said apparatus and tested without opening the pothead.

2. The combination with electrical apparatus of a pothead, a cable entering said pothead, a switch enclosed in said pothead for connecting said cable to said apparatus, a stuffing box carried by the pothead, and a conductive switch operating rod conductively connected to said cable while the switch 20 is open and extending through said stuffing box to a point accessible from outside the pothead.

3. The combination with electrical apparatus of a pothead, a cable entering said pothead, a switch enclosed in said pothead for connecting said cable to said apparatus, a 30

bushing extending through an opening in said pothead, a stuffing box carried by said bushing, and a conductive switch operating rod conductively connected to said cable while the 35 switch is open and extending into said bushing through the stuffing box.

4. The combination with electrical apparatus of a pothead, a switch enclosed in said pothead for connecting said cable to said apparatus, a bushing extending through an opening in said pothead, a stuffing box carried by said bushing, a conductive switch operating rod extending through the stuffing box and terminating within said bushing, and a 40 conductive handle arranged for detachable engagement with the outer end of said switch 45 operating rod.

5. The combination with an electrical apparatus casing, of a pothead mounted on said 50 casing, an apparatus lead and a cable entering said pothead, a switch enclosed in said pothead for connecting said cable and said apparatus lead, and a conductive switch operating rod conductively connected to said 55 cable while the switch is open and extending to a point accessible from outside said pothead while the pothead is closed.

In witness whereof, I have hereunto set my hand this 28th day of July, 1927.

FREDERICK F. BRAND.
